SPRING TENSIONED FUSE LINK

Alwin G. Steinmayer, Milwaukee, Wis., assignor
to Line Material Company, South Milwaukee,
Wis., a corporation of Delaware

Application October 1, 1934, Serial No. 746,479

10 Claims. (Cl. 200—127)

This invention relates to improvements in spring tensioned fuse links.

Spring tensioned fuse links have heretofore been provided with a flexible leader composed of numerous wires of exceedingly small cross-sectional area. These wires fuse easily and on high voltage currents, where there may be considerable arcing, an extremely large amount of metallic gas is generated when these wires fuse.

Accordingly, it is the principal object of this invention to provide a spring tensioned fuse link having a relatively non-flexible leader of comparatively large cross-sectional area, whereby to prevent fusing of the leader when the fusible portion of the link is destroyed and thereby keep the amount of gas generated by the arc at a minimum.

A further object is to provide a spring tensioned fuse link for expulsion fuses and in which only the conducting portions of the link proper are destroyed or discarded after the fuse blows.

In the drawing:

Fig. 1 is a view in side elevation partly in section illustrating an embodiment of this invention.

Fig. 2 is a fragmentary view in side elevation of the upper portion of the fuse link shown in Fig. 1.

Fig. 3 is an enlarged plan view as viewed from the bottom of Fig. 1.

Fig. 4 is a sectional view taken on the line 4—4 of Fig. 1 showing a fragmentary portion of the spring.

Fig. 5 is a fragmentary view in side elevation showing a modified form of this invention.

Fig. 6 is a view similar to Fig. 1 illustrating a modification of this invention.

Throughout the several views like parts are identified by the same reference characters.

In Fig. 1 the fuse cartridge comprises a tube of insulating material 10 open at the lower end and having at its upper end a contact ferrule 11 closed by means of a cap 12. Adjacent the lower end of the tube 10, a contact 13 is provided having a clamping nut 14 engaged with the stud 15 thereon.

The fuse link shown in Fig. 1 comprises a contact button 16 secured to the ferrule 11 by means of the cap 12, a terminal portion 17 apertured at 18 and 19 and having a reduced area 20 at its lower end provided with an aperture 21, a fusible section 22 having its upper end passed thru the aperture 21 and coiled about the terminal portion 17 at 22A, a leader composed of a strip of metal bent intermediate its ends to

provide an eye portion 23 and conducting portions 24 extending from the open end of the tube 10, the lower end of the fusible section 22 being passed thru the eye portion 23 and coiled about the conducting portions 24 at 22B adjacent the eye portion 23. The fusible section 22 may be soldered at each end to the terminal portion 17 and the conducting portions 24, the solder not being illustrated so that the manner in which the several elements are secured together may be clearly shown.

At the lower end of the tube 10, a coil spring 25 is provided encircling the lower ends of the conducting portions 24 of the link and having a portion 26 extending upwardly and hooked over the stud 15 to be clamped to the contact 13 by means of the clamping nut 14. Secured to the other end of the spring 25 by means of solder or otherwise, is a washer 27 flanged at 28 to partly encircle the lower end of the spring 25 and provided with a centrally located flanged opening 29 having its walls slotted at 30 to receive the lower ends of the conducting portions 24 of the fuse link when bent radially outwardly as illustrated at 31.

Conducting portions 24 of the leader are illustrated in Figs. 1, 2 and 3 as of the ribbon type. In Fig. 5 the conducting portions 24A of the leader are illustrated as cylindrical and shaped to provide an eye portion 23A for securing the fusible section 22 to the leader in much the same manner as that previously described with reference to Figs. 1 and 2. The modified structure shown in Fig. 6 is identical with the structure shown in Fig. 1 except at the lower end where the coil spring 25A encircles the lower end of the tube 10 and is provided with a washer 27A similar to the washer 27 in Fig. 1, but enlarged diametrically to receive the end of the tube within the flange 28A. The spring 25A may be secured to the washer 27A by soldering or otherwise and is provided with vertically extending portion 26A engaging the stud 15 and secured thereto by means of the clamping nut 14. As shown in Fig. 6 the washer 27A is electrically connected to the contact 13 by means of a flexible leader 32 secured to the washer in any suitable manner such as soldering, and clamped to the contact 13 by means of the clamping nut 14. Obviously, the washer 27 shown in Fig. 1 may be likewise electrically connected with the contact 13.

The fuse link is inserted in the tube 10 thru the upper end thereof when the cap 12 is removed and is secured therein with the contact

button 16 clamped to the ferrule 11 as illustrated. After the link has been thus inserted in the tube, the lower ends of the conducting portions 24 are bent as illustrated at 31 after 5 the spring 25 has been compressed to exert pressure upon the washer 27 and thus place the fusible section 22 under stress. When the fusible section 22 is severed, the spring 25 will move the remaining lower portion of the fuse link thru 10 the open end of the tube 10 and impart thereto an expelling motion which will cause that portion of the fuse link to continue its movement until it has cleared the tube.

When the fusible section 22 has fused, an arc 15 will be drawn in that section and will be extinguished before the lower ends of the conducting portions 24 have broken their contact with the washer 27. Thus, all arcing will be confined within the tube where it will not injure any of the 20 portions that are permanently a part of the cartridge. Furthermore, the arc will be confined to the area of the fusible section 22 by reason of the fact that the conductor portions 24 of the leader will not be fused and consequently an 25 excessive amount of metallic gas will not be generated during the time the circuit is being broken.

The operation of the device shown in Fig. 6 is similar to that of the device shown in Fig. 1. 30 The preferred embodiment of this invention is shown in Fig. 6. In Fig. 6 the spring 25A is guided by the lower end of the tube 10 and will therefore be maintained in alignment with the tube after the fuse link has been destroyed. 35 However, the flexible leader 32 will serve to conduct the major portion of the current and thereby protect the spring 25A against overheating under excessive current loads.

I claim:

40 1. In combination with an expulsion tube comprising an insulating tube closed at one end by a contact and having adjacent its other end and exteriorly thereof a second contact, a fuse link in said tube connected with the first mentioned contact and including a fusible section and a leader section of relatively large cross-sectional area extending thru the open end of said tube, a coil spring at the lower end of said tube connected at one end with the second mentioned contact 45 exteriorly of the tube, and an apertured washer engaged with the other end of said spring remote from the tube, said leader section extending thru the spring and aperture in said washer and having its extremity in hooked engagement 50 therewith to maintain said spring under compression, whereby when the fuse section is fused, the leader section will be expelled from said tube.

2. In combination with an expulsion tube comprising an insulating tube closed at one end by 60 a contact and having adjacent its other end and exteriorly thereof a second contact, a fuse link in said tube connected with the first mentioned contact and including a fusible section and a leader section of relatively large cross- 65 sectional area extending thru the open end of said tube, a coil spring at the lower end of said tube connected at one end with the second mentioned contact exteriorly of said tube, an apertured washer engaged with the other end of 70 said spring remote from the tube, said leader section extending thru the spring and aperture in said washer and having its extremity in hooked engagement therewith to maintain said spring under compression, whereby when the fuse 75 section is fused, the leader section will be expelled

from said tube, and a flexible conductor connecting said washer and second mentioned contact.

3. In an expulsion fuse, a spring tensioned fuse link comprising a fusible section and a leader portion composed of a single piece of conducting material of relatively large cross-sectional area bent intermediate its ends to provide an eye and conducting sections comprising a pair of spaced-parallel wires extending exteriorly of said tube, said fusible section being secured to the leader portion by passing one end thereof thru said eye and coiling it about said conducting sections at a point spaced from said eye. 5

4. An expulsion fuse including a tube open at its lower end having a pair of spaced contacts, 15 a fuse link in said tube connecting said contacts, said fuse link comprising a fusible section in said tube adjacent the upper end thereof and a relatively non-flexible section extending from said fusible section through the open end thereof, a coil spring coaxial with and engaged with said tube, said spring being disposed at the open end of the tube and secured to one of said contacts, said relatively rigid section extending through said spring and being bent radially of the tube 25 to hold the spring under compression and to maintain said fusible section under tension, and flexible means electrically connecting said relatively rigid section with one of said contacts.

5. An expulsion fuse including a coil tube extending from said fusible section through the open end of said tube having a pair of relatively spaced contacts, a fuse link in said tube for electrically connecting said contacts, said fuse link comprising a fusible section and a relatively non- 30 flexible section, a spring tensioning the fusible section, said spring being coaxial with said tube exteriorly thereof and engaged with the end of said tube, said spring being secured at one end to one of said contacts, a washer secured to the other end of said spring most remote from said tube said relatively non-flexible section extending through the washer and spring and being bent radially of said tube to engage said washer and hold said spring under compression, and a 35 flexible leader electrically connecting said washer and last mentioned contact.

6. An expulsion fuse including a tube open at its lower end and having a pair of spaced contacts, a fuse link in said tube, said fuse link comprising a fusible section in said tube and a pair of relatively non-flexible sections extending from said fusible section to the exterior of said tube, a coil spring coaxial with and engaged by the open end of said tube, said pair of conducting 55 sections being bent radially relative to the tube and in opposite directions to hold said spring under compression and to maintain said fusible section under tension, and a flexible leader electrically connecting the relatively non-rigid sections of said fuse links with one of said contacts.

7. An expulsion fuse including a tube having a pair of spaced contacts, a fuse link in said tube for electrically connecting said contacts and comprising a fusible section, and a relatively non- 65 flexible section bent to form a pair of parallel conducting portions extending exteriorly of said tube, and a coil spring coaxial with and engaged with said tube, said conducting portions being bent radially of said tube to engage the spring 70 and thereby to exert a tension on said fusible section, said spring being connected at one end with one of said contacts.

8. An expulsion fuse including a tube having a pair of spaced contacts, a fuse link in said tube 75

for electrically connecting said contacts and comprising a fusible section, and a relatively non-flexible section bent to form a pair of paralleling conducting portions extending exteriorly of said tube, a coil spring coaxial with and engaged with said tube, said conducting portions being bent radially of said tube to hold said spring under compression and thereby to exert a tension on said fusible section, said spring being connected at one end with one of said contacts, and a flexible leader electrically connecting the conducting portions of said fuse link with the last mentioned contact.

9. An expulsion fuse including a tube open at its lower end and having a pair of spaced contacts, one of which is adjacent the open end, a fuse link in said tube electrically connecting said contacts, said fuse link comprising a fusible section in said tube adjacent the upper end thereof and a relatively non-flexible section extending from said fusible section and through the open end of said tube, and a coil spring coaxial with and engaged with said tube, said spring being disposed at the open end and exteriorly of the tube and secured at one end to said contact adjacent said open end, said relatively rigid section extending through said spring and being bent radially of the tube and spring to releasably engage

and hold the spring under compression and to maintain said fusible section under tension, whereby when said fusible section has fused, said non-flexible section will drop freely from said tube and said spring will remain with said tube. 5

10. A fuse link in combination with an expulsion fuse cartridge open at one end and a coil spring secured to said cartridge and mounted exteriorly thereof adjacent said open end, said link comprising a contact portion within said cartridge, a relatively rigid leader extending from said open end, and a fusible portion within said cartridge electrically connecting said contact portion and rigid leader, said relatively rigid leader comprising a plurality of elongated rigid 15 wires each extending from said cartridge and through the coils of said spring and being substantially coextensive in length, said wires being connected with each other and with said fusible portion at their corresponding ends and being 20 in spaced and approximate parallel relation from said corresponding ends to the exterior of said cartridge, the ends of the wires exteriorly of said cartridge being bent radially of said coils, thereby to hold said spring under compression 25 and releasable therefrom.
